UNITED STATES PATENT OFFICE

96,152

DESIGN FOR A COMBINED SHOWER HEAD AND SPRAY GUIDE

Roy H. Zinkil, Oak Park, Ill., assignor to Crane
Co., Chicago, Ill., a corporation of Illinois

Application April 11, 1935, Serial No. 56,335

Term of patent 14 years

To all whom it may concern:

Be it known that I, Roy H. Zinkil, a citizen of the United States, residing in Oak Park, in the county of Cook and State of Illinois, whose post office address is 406 North Cuyler Avenue, Oak Park, Illinois, have invented a new, original, and ornamental Design for Combined Shower Head and Spray Guide, of which the following is a specification, reference being had to the accompanying drawing, forming part thereof.

In the drawing:

Fig. 1 is a front elevation of the combined shower head and spray guide embodying my design.

Fig. 2 is a side elevation of the combined shower head and spray guide.

Fig. 3 is a plan view of the combined shower head and spray guide looking into the discharge opening.

I claim:

The ornamental design for a combined shower head and spray guide, substantially as shown.

ROY H. ZINKIL.
